UNITED STATES PATENT OFFICE.

AMOS L. KNIGHT, OF PHILADELPHIA, PENNSYLVANIA, ASSIGNOR TO LANSTON MONO-TYPE MACHINE COMPANY, OF PHILADELPHIA, PENNSYLVANIA, A CORPORATION OF VIRGINIA.

CASTING-MACHINE FOR ELEMENTS OF PRINTING-FORMS.

1,922,415.

Specification of Letters Patent. Patented Apr. 10, 1917.

Application filed October 3, 1914. Serial No. 864,894.

To all whom it may concern:

Be it known that I, AMOS L. KNIGHT, a citizen of the United States, residing at Philadelphia, in the county of Philadelphia and State of Pennsylvania, have invented certain new and useful Improvements in Casting-Machines for Elements of Printing-Forms; and I do hereby declare the following to be a full, clear, and exact description 10 of the same, reference being had to the accompanying drawings, forming part of this specification, and to the figures and letters of reference marked thereon.

This invention relates to apparatus for 15 casting elements of printing forms such as rules, leads, quads, type, etc., and the apparatus adopted for illustrating the invention is one designed more especially for use in connecting with a monotype casting machine, 20 for example, the machine set forth and described in Letters Patent No. 625,998, granted to J. S. Bancroft, May 30, 1899. In the machine illustrated, the mold, matrix carrier, and centering mechanism of the patented machine have been omitted and the 25 mechanism of the present invention substituted, as will hereinafter appear, but it will be understood that the invention may be incorporated in a machine designed for the 30 special function of casting elements of printing forms without having incorporated therein the refinements of mechanism embodied in the monotype casting machine for producing accurately justified lines of type, and 35 therefore the present invention is susceptible of embodiment in a comparatively simple machine.

The principal objects to be accomplished are first the casting of the elements in 40 indeterminate lengths adapted to be subsequently severed to form lines, rules or leads of the desired length for any particular printing form, and secondly, to permit of the casting of such elements free from cavities or defects, and of accurately proportioned dimensions to correspond either to the point size of the elements composing the form, or to bear such relation to the same that the elements of the form may be locked up without 45 permitting of any looseness or play of the elements. Other objects of the invention are to provide mechanism which will produce the elements in indeterminate lengths economically and from molten metal such as is

commonly employed in the type casting art 55 for casting type characters and commonly known as type-metal, thus putting it within the capacity of the ordinary printing establishment to produce all of the elements entering into the printing form at such time as 60 the same may be needed and of proper size as to fit the work in hand.

Referring to the accompanying drawings,—

Figure 1 is a top plan view of an apparatus embodying the present improvements, 65 certain of the parts being broken away, and some of the parts of the monotype machine used in connection therewith being shown in conventional outline.

Fig. 2 is a front elevation of the major portion of the mechanism illustrated in Fig. 1.

Fig. 3 is a perspective view of the mold and its associated parts, separate from the 75 machine.

Fig. 4 is a top plan view of the same.

Fig. 5 is an elevation looking at the rear side of the mold and associated parts shown in Figs. 3 and 4.

Fig. 6 is a perspective view of the front type block.

Fig. 7 is a similar view of the rear type block.

Fig. 8 is a sectional view in a plane longitudinally of the mold and substantially on the line 8—8 of Fig. 9.

Fig. 9 is a transverse section substantially on the line 9—9 of Fig. 8.

Fig. 10 is an elevation looking at the left 90 hand end of the mold and associated parts shown in Figs. 3 and 8, but omitting the mold blade operating bar.

Fig. 11 is a detail top plan view of a portion of the mold showing the matrix, matrix 95 locating plate and matrix abutment.

Fig. 12 is a perspective view of the mold blade and gate pusher employed for the casting of printers' rules.

Fig. 13 is a perspective view of the gate 100 pusher separate from the mold blade.

Fig. 14 is a detail section substantially on the line 14—14 of Fig. 4.

Fig. 15 is a section in a horizontal plane, with the parts shown in a more or less dia- 105 grammatic manner, through the mold and associate parts to illustrate the operation of the mold blade and cutter.

Figs. 16 and 17 are diagrammatic illustrations of a portion of a printer's rule and the mold blade which co-operates therewith to advance the rule and to form the space 5 for the reception of succeeding increments of molten metal.

Fig. 18 is a view corresponding to Fig. 12 showing a mold blade for forming printers' leads.

10 Fig. 19 is a perspective view of a filler blade for use in connection with the mold blade shown in Fig. 18.

Fig. 20 is a perspective view of the support for the filler blade.

15 Fig. 21 is a perspective view of a matrix for forming printers' rules with multiple printing edges.

Like letters of reference in the several figures indicate the same parts.

20 The mechanism illustrated is, as before stated, designed particularly for use in connection with a monotype casting machine, and in order that the relationship of the parts may be properly understood from the 25 accompanying drawings, there is shown in Figs. 1 and 2 certain conventional parts of the monotype machine of the patent hereinbefore referred to, such parts being identified by reference numbers corresponding to 30 the numbers found in the patent. In Fig. 1, which is a top plan view, there is seen the melting pot 184, the pump which may be identified by its operating lever 215, the driving pulleys 373, the cam shafts 370 and 35 371 with their connecting gearing 372, cam 384 for operating the lever 246, for the cross blade and type carrier and cam 381 for operating the centering pin actuating lever 58, which lever is in the form of a bell 40 crank pivotally mounted at its angle in a bracket on the main frame, as usual. The centering mechanism for the die carrier (with the exception of the lever 58) and the mechanism for moving the die carrier and 45 for effecting justification, has all been omitted, and in place of the usual mold, a mold has been substituted in which the molten metal is given form and from which it is fed or ejected in a direction toward the 50 melting pot or in line with the cross blade and type carrier movement of the ordinary monotype machine.

The mold is indicated generally by the reference numeral 1 in Figs. 1 and 2, and it 55 is clamped firmly in place on the frame of the machine by clamps 2 of any suitable character. The location corresponds to the location of the mold in the monotype machine, and it is adapted to receive molten 60 metal from a nozzle which is controlled by the pump mechanism, as heretofore.

For convenience and accuracy of construction the mold is preferably a built-up structure and embodies a mold base 3 formed 65 with a channel therethrough in the direc-

tion of the movement of the mold blade, thus providing front and rear upwardly extending portions 4 which are connected across the top of the mold by tie bars 5. There are suitable co-operating shoulders and connecting screws and the shoulders are preferably formed by grooves 6 in the mold base in which projections 7 on the tie bars seat, whereby an exceedingly rigid structure is formed and one capable of being finished 70 with a high degree of accuracy by known economical shop methods. Confined within the channel extending through the mold base are the type blocks between which the cavity for the reception of the molten metal is 75 formed, and these type blocks are preferably in the form of bars which extend out at each end of the mold base and are adapted for the reception, between such extended portions, of point blocks which will determine the 80 width of the mold cavity and consequently the point size of the element being cast. The rear type block 8, Fig. 7, is preferably formed with a smooth inner face and constitutes one wall of the mold cavity as well as 85 the wall of the passage in which the mold blade works, and of the exit opening through which the formed element is ejected. The front type block may be of similar construction and arranged to be placed in opposition 90 thereto, but it is preferably formed in two sections 9 and 10 for convenience in manufacture, inasmuch as it is one of the objects of the present invention to provide at one side of the mold cavity a channel and exit 95 opening through which air and a portion of the molten metal from the mold cavity may escape, in the form of a more or less spongy mass which, for convenience may be called a gate, lying at one side of the element and 100 adapted to be subsequently severed therefrom. By reference to Fig. 6 it will be seen that the upper front type block 9 substantially corresponds in outline to the upper half of the rear type block 8 and the lower 105 front type block 10 substantially corresponds in outline to the lower half of the rear type block 8, while between the two sections is formed a narrow space 11, and this space widens out within the type block in the form 110 of a channel which is dove-tail or triangular in cross section, as indicated at 12. The said channel 12 and entrance slot 11 are preferably slightly tapered, or of increasing cross section toward the exit end of the block. 115

The blocks 8, 9 and 10 are placed face to face in the mold base with the projections 13, 14, 15 and 16 in position against the ends of the mold base and sides of the tie bars respectively, as shown clearly in Fig. 8, while between the projections there are placed point blocks 13^a, 14^a, 15^a, and 16^a which are of a thickness corresponding to the point size of the element to be cast and thus define the width of the mold cavity. 120

Where the front type block is made in two sections as hereinbefore described, the upper section 9 is preferably made rigid with the lower section 10 by being fixed accurately thereto and supported by an upwardly extending portion 10^a of the section 10 to which it is connected by screws or other suitable fastening, as will be readily understood by an inspection of Fig. 9, which shows 10 these parts in cross section:

The two type blocks forming between them the mold cavity, are positioned laterally of the mold base by a packing plate 17 in rear of the rear type block and by a pressure screw 18 passing through the front projection 4 of the mold base and adapted to bear against the front type block. This pressure screw in the preferred construction is operated periodically in time with 20 the feeding of the element being cast, and for this purpose it is conveniently provided with a lever end 19 (Fig. 2) which through connections to be presently described, is adapted to be operated from the centering 25 pin actuating lever 58, to clamp the sides of the mold cavity together during the casting operation and to release such pressure during the feeding of the element forwardly in the mold cavity.

30 The bottom of the mold cavity is formed by the mold base, and is provided with a nozzle opening 20 (Fig. 8) through which the molten metal is injected into the mold cavity from a nozzle 20^a having its opening slightly inclined. The top of the mold cavity is formed by a matrix or member which gives shape to the upper face of the element being cast, and where printers' rules are to be formed, this matrix, indicated in the 35 drawings at 21, is provided in its lower face with a groove 22 of proper cross sectional shape to give form to the printing edge of the rule, but it will be understood that one or more of such grooves may be 40 formed in the matrix, depending upon the character of the printing surface desired. As shown in the drawings, with the exception 45 of Fig. 21 the matrix is provided with a single V-shaped groove, being designed 50 to make a printer's rule with a single narrow printing edge, but in Fig. 21 a matrix is illustrated in which a plurality of grooves 22^a are provided for making multiple printing edges on the rule. In case printers' 55 leads are to be formed provision is made whereby the height of the mold cavity will be correspondingly reduced as will be hereinafter described.

60 The matrix 21 is adapted to seat against a matrix abutment 23 mounted on the upper face of the rear type block and it is positioned against such abutment by locating plate 24 resting on the front type block between the tie bars and having a pin 24^a, Fig. 11, to limit the sliding movement of the

plate between the tie bars. The matrix is held firmly in position by a matrix clamp 25 having two surfaces 25^a for coöperation with one edge and the top of the matrix, and an inclined surface 25^b for coöperation 70 with a corresponding inclined surface on the matrix abutment 23, whereby when the matrix clamp is forced down by its clamping screw 26 the matrix will be forced downwardly and against its abutment where it will be 75 held with precision and in such relation to the type block as to prevent any liability of molten metal escaping through the joints.

The mold blade 27 is of a thickness which corresponds to the point size of the element 80 being cast and is adapted to reciprocate between the proximate faces of the type blocks from the forward position indicated in Fig. 8, where its front edge is just forward of the nozzle opening, to a position in rear of 85 said nozzle opening which will determine the width of the cavity to be filled by molten metal. The movement of the mold blade is preferably so adjusted that when at the rear extreme of its movement its upper edge 90 will register with the rear end of the groove in the matrix, although the range of movement is susceptible of adjustment through mechanism which will be hereinafter referred to.

95 The forward end of the mold blade which, when retracted, forms the rear end wall of the mold cavity, is shaped to give the desired conformation to the rear edge of the type metal when congealed, and in carrying out 100 the present invention in a practical way it has been found important to give the rear edge of the type metal a conformation which will facilitate the fusion of the metal with the next increment injected into the mold 105 cavity. It is for this reason that the upper portion of the mold blade is curved rearwardly, to thereby form an overhanging or inclined face at the rear edge of the congealed type metal along and against which 110 the inflowing molten metal will travel in filling the mold. The relation of this rear edge of the type metal to the incoming jet of molten metal will be understood from 115 an inspection of Fig. 8 which shows the front end of the mold blade in its forward position, and consequently said front edge conforms to the shape of the rear edge of the type metal which has been advanced by the forward movement of the mold blade. 120 Owing to this formation, the rear edge of the congealed metal is subjected to the direct contact of the incoming metal which constantly travels along said edge until the mold cavity is filled, and it is believed that 125 this formation also materially assists in discharging the air from the mold cavity during the entrance of the molten metal inasmuch as any tendency toward a cellular formation or the formation of cavities in the 130

casting is always found to exist at a point considerably below the upper edge and consequently the upper edge is perfect and solid so as to present a proper printing surface.

- 5 The provision of the transverse opening into the channel at one side of the mold cavity permits of the complete discharge of all air from the cavity and the making of a casting solid throughout. In practice the 10 best results have been secured in the making of leads and rules when this opening extends clear along the side of the cavity, and is located at or slightly below the center of the cavity.
- 15 The metal which enters the channel and forms the gate is connected with the side of the element being cast by a very thin attachment, and it is preferably fed out of the channel simultaneously with the element to 20 which it is attached. Such feeding movement of the gate is preferably effected by a gate pusher 28 conveniently operated directly by the mold blade, the connection between the gate pusher 28 and mold blade being formed by a foot 29 on the rear end of the pusher which enters a socket or opening 30 in the mold blade.

At its rear end the mold blade 27 enters the mold between upper and lower mold 30 blade shoes 31 and 32, respectively, and its forward movement is arrested by a mold blade stop 33, extending into the usual opening in the mold blade and attached to the mold blade base by a screw 34. A mold 35 blade stop of this character leaves the opposite side of the mold blade exposed for the attachment of the mold blade operating bar 35. The bar 35 at its forward end enters a recess 37 in the type block at the side of the mold blade, and is pivotally connected to the blade by a transverse stud or pin 36 (see Fig. 15.) The rear or outer end of the mold blade operating bar is connected with the type carrier lever 246 through an adjustable 40 connecting member 38 and spring box 39 embodying springs 39^a, whereby the movement of the blade may be arrested while the lever 246 makes its full movement.

Rearward movement of the mold blade is 50 limited by a stop 40 having a shoulder against which the blade strikes, and the stop is adjustably clamped (as by set screws 40^a passing through slots 40^b) to the pin block of the monotype machine. Its adjustment is 55 effected by a set screw 41 adapted to bear against a stop 42 immovably clamped (as by screw 42^a) in position on the frame, all as shown clearly in Figs. 1 and 2.

The rule being cast issues from between 60 the type blocks and passes through a friction clamp one member of which is a gate shear serving to detach the gate from the side of the element and to form a smooth face on the side should there be any roughness or projecting metal thereon.

By reference to Figs. 3, 4 and 5 it will be seen that in an extension of the mold base there is mounted a transverse clamp yoke 43 to one upturned end of which the gate shear 44 is secured, while opposed to the flat 70 face of said gate shear is a friction block 45 advanced by spring pressure through the medium of a spring 46 located within a bore in the block 45 and adapted to be held up to its work by a plunger 47 forming the inner 75 end of a friction clamp adjusting screw 48 passing through the end of the clamp 43 opposite that to which the shear is secured (see Fig. 14 of the drawings). The gate shear has its cutting edge 44^a curved downwardly as shown in Fig. 5 whereby the gate will be sheared from the side of the casting, and the shear is located immediately over the melting pot 184, as shown in Figs. 1 and 2, whereby the metal detached from 80 the casting will drop directly into the melting pot and be again utilized in the making of further castings. The strip which is being cast passes over the melting pot and is received by any suitable receiver or, if so 85 desired, immediately cut up into lengths to suit the printing form for which it is made.

Should lubrication of the mold cavity be desired it may be effected through a lubricant pocket and groove indicated in Fig. 95 6 at 49.

To best adapt the centering pin actuating lever 58 for operating the pressure screw 18 through its actuating lever 19, a casting is clamped to the forward end of the lever 100 58. As shown in Figs. 1 and 2, this casting is provided with a forwardly projecting arm 50 to the end of which a connecting rod 51 is attached through connections which will permit of a yielding movement of the 105 connecting rod when the actuating lever is depressed. This result may be attained by a connecting rod 51 which at its lower end is pivotally connected with the arm 19 of the screw 18 and at its upper end passes through 110 an eye in the casting 50. A spring 52 surrounding the connecting rod 51 below the casting 50 serves as the medium whereby downward pressure may be imparted to the lever 19 and upward movement of the lever 19 115 is effected through the connecting rod itself, which is provided with an adjustable stop or nut 53 above the casting 50.

The casting 50 referred to is provided with an opening to fit the stud or projection 120 54 on the side of the lever 58' and with screws and thumb nuts 55 properly positioned to operate with the actuating lever of the ordinary monotype machine.

Where it is desired to cast elements for 125 printers' forms the upper edges of which are below the printing surface of the forms, as for example, ordinary low printers' leads, this is accomplished by reducing the height of the mold cavity and providing a mold 130

blade of corresponding height. Conveniently the mold blade will be of the usual construction heretofore described, save that its forward upper edge will be cut-away as shown at 56, in Fig. 18, and to form the upper edge wall of the mold cavity a filler blade 57 is provided which in thickness corresponds to the thickness of the mold blade and this filler blade is held in place by a support 59 (Fig. 20) which is in turn mounted in position in the mold in the manner hereinbefore described in connection with the matrix. The filler blade may be made to form elements of the height of low quads and should shoulder high elements be desired a matrix block having a plane face may be substituted for the matrix heretofore described.

With the construction described it becomes a comparatively simple and inexpensive matter to cast the elements for printers' forms, such as rules, and high and low leads, etc., in continuous lengths and to subsequently sever the same into the desired lengths.

The operation of the particular embodiment of the invention described is substantially as follows:

Assuming that the mold blade has advanced, pushing before it the portion of the printers' rule previously cast, and has retracted or is in the act of retracting to leave a space between the end of the mold blade and rear edge face of the portion of the rule already cast, the pump mechanism comes into operation to bring the nozzle of the pump into the opening 20 and inject a quantity of molten metal sufficient to fill the mold cavity and to force a portion of the molten metal together with the air previously in the cavity out into the channel at the side of the cavity. In passing into the mold cavity the molten metal flows along the edge face of the previously congealed metal of the rule and is deflected thereby so as to set up a swirling movement in the cavity. The impingement and flow of the molten metal against and along the face of the congealed metal raises the heat of the latter to a point where fusion will take place and effects a perfect union of the two increments or portions of the metal.

The heat at which the mold operates is regulated by a cooling system such as is common in molds now employed in the monotype casting machines, as for example, by the circulation of a cooling medium through channels indicated at 60 in Fig. 9, and the temperature is preferably proper for effecting the rapid congealing of the molten metal as soon as the mold cavity is filled. Just before or during the time the metal is being injected and congealed in the mold cavity the actuating lever 58 is operated to set up the pressure screw on the type

blocks so as to clamp all of the parts tightly together and as soon as the metal is congealed this pressure is withdrawn by the reverse movement of the actuating lever 58 and the mold blade is immediately advanced 70 to feed the casting forwardly.

These operations are repeated in succession until the desired length of rule has been cast and as the rule issues from between the clamps the gate at the side thereof is severed 75 and drops down into the melting pot where it is melted for subsequent use.

A diagrammatic representation of the operation is found in Figs. 16 and 17 of the drawing, wherein the completed rule is indicated at 65, the severing of the gate from the side of the rule at 66, and the end of the mold blade in its advanced position after having fed the rule forwardly, at 67. When the mold blade retracts to the position indicated in Fig. 17, it leaves a space 68 in which the subsequent casting is effected, and this space, it will be understood, may be regulated in size by the adjustment of the movement of the mold blade and by the introduction of different point blocks and mold blades where the point size is to be changed, as well as by the substitution of different matrices or filler blades where the style of the printing surface is to be changed or 95 where the printing surface is to be entirely eliminated and shoulder high or low elements formed.

By giving the forward end of the mold blade a curvature such as shown, any tendency of the metal to wedge up against the matrix is effectually overcome.

Features disclosed herein but not specifically claimed, such as the method of forming elements of printing forms, both in increments fused together and in unfused sections cast successively in contact with each other, the filler blade which is substituted for the matrix, and the mold blade with its pusher, are claimed in my contemporaneous 110 applications Serial Nos. 88,334; 111,741; 120,821; and 146,492.

Having thus described my invention, what I claim as new and desire to secure by Letters Patent of the United States, is:

1. An apparatus for casting type metal elements for printing forms, embodying means for confining molten metal, in contact with a surface of a previously congealed portion of the element being cast 120 whereby the two portions are caused to unite by fusion, means for intermittently advancing the element with relation to the confining means as succeeding increments congeal, and means for forcibly injecting 125 molten metal within the confining means to form succeeding increments of the element.

2. An apparatus for casting type metal elements for printing forms embodying means for confining a body of molten metal 130

in contact with a surface of a previously congealed portion of the element being cast, whereby the two portions are caused to unite by fusion, means for intermittently advancing the element as succeeding increments congeal, means for intermittently injecting molten metal within the confining means, and means for directing the incoming metal along the face of the previously congealed portion of the element.

3. An apparatus for casting type metal elements for printing forms embodying a mold having a cavity in which the metal congeals, said cavity being open at one side for the exit of the congealed metal and provided with an opening for the entrance of molten metal, means for advancing the metal toward the exit side of the cavity to form a space in rear of the same, and means for injecting molten metal into such space.

4. An apparatus for casting type metal elements for printing forms embodying a mold having a cavity in which the metal congeals, said cavity being open at one side for the exit of the congealed metal and provided with an opening for the entrance of molten metal, means to retain the congealed metal in position to form one wall of the cavity and a reciprocatory blade for advancing the congealed metal to form a space for the reception of a succeeding increment of molten metal.

5. An apparatus for casting type metal elements for printing forms embodying a mold having a cavity in which the metal congeals, said cavity being open at one side for the exit of the congealed metal and provided with an opening for the entrance of molten metal, means to retain the congealed metal in position to form one wall of the cavity, a reciprocatory blade movable in the cavity for advancing the congealed metal, and means for injecting molten metal in the space left by the rearward movement of the blade.

6. An apparatus for casting type metal elements for printing forms embodying a mold having a cavity in which the metal congeals, said cavity being open at one side for the exit of the congealed metal and provided with an opening for the entrance of molten metal, means to retain the congealed metal in position to form one wall of the cavity, a reciprocatory blade movable in the cavity for advancing the congealed metal, said blade having the upper edge of its end face located in a transverse plane in rear of the transverse plane of the lower edge of its end face, and means for injecting molten metal in the space left by the rearward movement of the blade.

7. An apparatus for casting type metal elements for printing forms embodying a mold having a cavity in which the metal congeals, said cavity being open at one side

for the exit of the congealed metal and provided with an opening for the entrance of molten metal, means to retain the congealed metal in position to form one wall of the cavity, a reciprocatory blade movable in the cavity for advancing the congealed metal, said blade having its end face extending upwardly and rearwardly, and means for injecting molten metal in the space left by the rearward movement of the blade.

8. An apparatus for casting type metal elements for printing forms embodying a mold having a cavity in which the metal congeals, said cavity being open at one side for the exit of the congealed metal and provided with an opening for the entrance of molten metal, means to retain the congealed metal in position to form one wall of the cavity, a reciprocatory blade movable in the cavity for advancing the congealed metal, said mold blade having the portion of its end face remote from the entrance opening inclined rearwardly, and means for injecting the molten metal in the space left by the rearward movement of the blade.

9. An apparatus for casting type metal elements for printing forms embodying a mold having a cavity in which the metal congeals, said cavity being open at one side for the exit of the congealed metal and provided with an opening for the entrance of molten metal located at substantially right angles to the exit side of the cavity, means to retain the congealed metal in position to form one wall of the cavity in proximity to the entrance opening, a reciprocatory mold blade movable in the cavity for advancing the congealed metal to form a space for the entrance of molten metal, said mold blade normally forming one wall of the cavity and having its end face extending substantially parallel with the axis of the entrance opening in that portion of the blade in proximity to the entrance opening and curving rearwardly in that portion of the blade remote from the entrance opening, whereby a corresponding form will be given to the edge of the congealed metal, and the incoming molten metal will be deflected by the curved face of the congealed metal, and means for injecting molten metal into the space left by the rearward movement of the blade.

10. An apparatus for casting type metal elements for printing forms embodying a mold having a cavity in which the metal congeals, said cavity being open at one side for the exit of the congealed metal and provided with an opening for the entrance of molten metal, a movable blade forming one wall of the cavity, means for retaining the congealed metal in position to form the wall of the cavity opposite the blade, and a removable member forming the top of the mold cavity.

11. An apparatus for casting type metal elements for printing forms, embodying a

5 mold having a cavity in which the metal congeals, said cavity being open at one side for the exit of the congealed metal and provided with an opening for the entrance of molten metal, a blade forming one wall of said cavity, means for retaining the congealed metal in position to form the wall of the cavity opposite said blade, and a matrix having a groove therein open at one end, forming the 10 top wall of the mold cavity.

12. An apparatus for casting type metal elements for printing forms, embodying a mold having a cavity with an entrance opening for the molten metal and an opening for 15 the escape of air and a portion of the metal from the cavity, and means for discharging the congealed metal from within the mold cavity, and means for discharging the congealed metal from the air escape opening.

13. An apparatus for casting type metal elements for printing forms, embodying a mold having a cavity with an entrance opening for the molten metal and a vent opening for the escape of air and a portion of the 20 metal from the cavity, said opening extending through the side wall of the cavity at a point remote from the ends whereby the air may escape from the central part of the cavity while the latter is being filled with 25 molten metal, and means whereby the congealed metal may be discharged from the cavity and vent opening.

14. An apparatus for casting type metal elements for printing forms, embodying a 30 mold having a cavity in which the molten metal congeals, said cavity having an entrance opening for molten metal and an elongated narrow opening for the escape of air and a portion of the metal from the cavity, means for severing and completely 35 removing such metal from the metal congealed within the cavity, and means for clearing the air discharge opening of metal congealed therein.

15. An apparatus for casting type metal elements for printing forms, embodying a mold forming a cavity for confining a body of molten metal while congealing to form the element, said mold having an opening 40 for the admission of molten metal, an elongated channel communicating with the mold cavity and into which air and a portion of the metal may escape from the mold cavity and congeal, and a pusher working in said 45 channel to discharge the metal therefrom.

16. An apparatus for casting type metal elements for printing forms, embodying a mold forming a cavity for confining a body of molten metal while congealing to form the element, said mold having an opening 50 for the admission of molten metal, a channel communicating with the mold cavity through an elongated reduced opening and into which air and a portion of the metal 55 may escape from the mold cavity, and a

pusher working in said channel to clear the same.

17. An apparatus for casting type metal elements for printing forms, embodying a mold forming a cavity for confining a body 70 of molten metal while congealing to form the element, said mold having an opening for the admission of molten metal, a channel communicating with the mold cavity and into which air and a portion of the metal 75 may escape from the mold cavity, a pusher working in said channel to clear the same and means for severing the metal escaping into the channel from the element.

18. An apparatus for casting type metal elements for printing forms, embodying a mold forming a cavity for confining a body 80 of molten metal while congealing to form the element, said mold having an opening for the admission of molten metal, a channel 85 communicating with the mold cavity through a reduced opening, and into which air and a portion of the metal may escape from the mold cavity, a pusher working in said channel to clear the same, and means 90 for severing the metal escaping into the channel from the element.

19. An apparatus for casting type metal elements for printing forms, embodying a mold having a cavity in which the metal 95 congeals, said cavity being open at one side for the exit of the congealed metal and provided with an opening for the entrance of molten metal, and also having a channel extending parallel and communicating with 100 the mold cavity, whereby a portion of the molten metal will enter said channel from the cavity, means for retaining the congealed metal in position to form one wall of the mold cavity and to close the exit of the 105 channel, means for feeding the congealed metal forward to leave a space for the entrance of a subsequent increment of molten metal, and means for injecting molten metal into said space. 110

20. A mold for casting type metal elements for printing forms, having a mold cavity provided with an opening for the admission of molten metal, one side of said cavity being open for the exit of the metal 115 congealed in the cavity, said mold also having a channel extending parallel with the mold cavity and communicating therewith through a narrow elongated opening through which the air and a portion of the metal from the 120 cavity may escape into the channel, and means for retaining the congealed metal in the exits of the cavity and channel.

21. An apparatus for casting type metal elements for printing forms having a cavity 125 in which the metal congeals to form the element, a channel extending parallel with said cavity and communicating therewith through a narrow opening, said cavity, channel and communicating opening being open 130

at one side for the exit of the congealed metal, means for advancing the congealed metal toward the exits, means for retaining the congealed metal in the exits, and means 5 for injecting molten metal into the space behind and in contact with the rear face of the congealed metal.

22. An apparatus for casting type metal elements for printing forms embodying a 10 mold having a cavity in which the metal congeals, said cavity being open at one side for the exit of the congealed metal and also having a channel extending parallel and communicating with said cavity through a 15 narrow opening, means for advancing the metal congealed in said cavity through the exit opening, means for clamping the congealed metal to retain the same in the exit opening to form one wall of the cavity, a 20 cutter for severing the metal congealed in the channel from that congealed in the mold cavity, and means for injecting molten metal in the space in rear of the congealed metal.

23. A mold for casting type metal elements for printing forms embodying a 25 base block, parallel independent type blocks mounted in the base block, a mold blade mounted to reciprocate between the type blocks, a fixed matrix forming one wall of 30 the cavity in which the casting is formed, means for pressing the type blocks toward each other during the casting operation, and means to retain the congealed metal in position to form the wall of the cavity opposite 35 that formed by the mold blade.

24. In a mold for casting type metal elements for printing forms, the combination with the base block having an opening therein for the entrance of molten metal, parallel 40 type blocks mounted in said base block to form the side walls of the mold cavity, a reciprocatory mold blade mounted between the type blocks to form one edge wall of the mold cavity and movable to advance 45 the congealed metal into a position to form the opposite wall of the mold cavity, and means to support the congealed metal in such position.

25. In a mold for casting type metal elements for printing forms, a mold block having 50 an opening therein for the entrance of molten metal, a pair of type blocks mounted in said base block and forming between them a channel with parallel walls, a mold 55 blade working between said type blocks to form one wall of the cavity in which the metal is given shape, the proximate faces of the type blocks beyond the mold blade forming an open passageway for the exit of the 60 congealed metal, and to retain said congealed metal in position to form the wall of the cavity opposite the end of the mold blade, and a matrix forming the top wall of the mold cavity.

26. A mold for casting type metal ele-

ments for printing forms embodying a base block, two type blocks mounted in said base block and having parallel proximate faces between which the casting is given shape, a mold blade mounted to reciprocate in the space between said type blocks, a matrix, 70 means for clamping said matrix on said type blocks above the mold blade, said base block having an entrance opening for molten metal and the proximate faces of the type blocks 75 being extended on the opposite side of said entrance opening from the mold blade, whereby metal congealed between the type blocks will be retained in position to form a wall of the mold cavity opposite the end 80 of the mold blade, and means for limiting the reciprocatory movements of the mold blade.

27. An apparatus for casting type metal elements for printing forms embodying a 85 mold having a base block, type blocks mounted in said base block and having parallel proximate faces extending beyond the cavity in which the casting is given shape, whereby the congealed metal will be retained in position to form one wall of the 90 cavity, means for feeding the congealed metal and means for injecting molten metal in the space left by the advance of the congealed metal.

28. An apparatus for casting type metal elements for printing forms embodying a 95 mold having a base block, type blocks mounted in said base block and having parallel proximate faces extending beyond the cavity in which the molten metal is given shape whereby the congealed metal will be retained in position to form one wall of said 100 cavity, a reciprocatory mold blade mounted between the type blocks for advancing the congealed metal, means for limiting the reciprocatory movements of the mold blade, and means for injecting molten metal in the cavity left by the advance of the congealed metal and rearward movement of the mold 110 blade.

29. An apparatus for casting type metal elements for printing forms embodying parallel independent type blocks having projections thereon, point blocks mounted between corresponding projections on the type blocks to determine the point size of the element cast between the blocks, means for injecting molten metal between the blocks in contact with the rear face of metal previously injected and congealed, and means for advancing the congealed metal between the blocks. 115

30. In a mold for casting type metal elements for printing forms, a base block having a channel extending therethrough, tie 120 bars connecting the sides of said channel, type blocks mounted in said channel and having parallel proximate faces forming the side walls of the cavity for giving shape to the molten metal, said side walls extending 125

beyond the mold cavity to retain the congealed metal in position to form one wall of the cavity, and a mold blade mounted to reciprocate between said mold blocks for advancing the congealed metal.

31. In a mold for casting type metal elements for printing forms, a base block having a channel formed therethrough, tie bars connecting the side walls of said channel, type blocks mounted in parallelism in said channel and having projections at the ends of the base block whereby they are retained in position, point blocks mounted between the type blocks for determining the point size of the element being cast, the proximate faces of said type blocks being extended beyond the cavity in which the casting is given shape for retaining the congealed metal in position to form one wall of the cavity, a reciprocating mold blade forming the opposite wall of the cavity, and a matrix mounted on the type block for forming the top wall of the mold cavity.

32. A mold for casting type metal elements for printing forms, embodying a mold base, type blocks mounted in said mold base, and having parallel proximate faces forming between them the mold cavity, said faces extending beyond the mold cavity for retaining the congealed metal in position to form one wall of the cavity, a mold blade working between the type blocks for advancing the congealed metal, and a friction clamp having yielding clamping members between which the congealed metal passes.

33. A mold for casting type metal elements for printing forms, embodying a mold base, type blocks mounted in said mold base and having substantially parallel proximate faces forming between them the mold cavity and extending beyond said cavity to retain the congealed metal in position to form one wall of the cavity, a mold blade for advancing the congealed metal between the type blocks, and a friction clamp having yielding friction members between which the congealed metal passes, and means for regulating the pressure of the friction members.

34. In an apparatus for casting type metal elements for printing forms, the combination with the melting pot in which the metal is melted, a pump for transferring the melted metal to a molding mechanism, and a molding mechanism embodying means for confining the molten metal while congealing, means for advancing the congealed metal over the melting pot, and means for severing a portion of the congealed metal, located immediately over the melting pot whereby the severed metal is deposited in the melting pot to be remelted.

35. An apparatus for casting type metal elements for printing forms embodying a mold provided with a cavity having parallel side walls, said side walls being extended beyond the cavity to retain the congealed metal in position to form one wall of the cavity, a mold blade for advancing the congealed metal between said walls, a cutter bearing against one side of the metal issuing from between said walls, a spring for advancing said cutter with a yielding pressure and means for adjusting the tension of the spring.

36. An apparatus for casting type metal elements for printing forms embodying a mold provided with type blocks having parallel proximate faces forming the side walls of the cavity in which the metal is congealed, said side walls extending beyond said cavity to retain the congealed metal in position to form one wall of the cavity, and one of said type blocks having therein a longitudinal channel communicating with the space between the type blocks by a narrow elongated opening.

37. A type block for casting apparatus of the character specified formed in longitudinal sections with a channel between said sections in communication with the face of the type block through an elongated narrow opening.
